US0D1040778S

(12) **United States Design Patent** (10) **Patent No.:** **US D1,040,778 S**
(45) **Date of Patent:** **** Sep. 3, 2024**

(54) **BLUETOOTH HEADSET**

(71) Applicant: **RunMing Li**, Guangdong (CN)

(72) Inventor: **RunMing Li**, Guangdong (CN)

(**) Term: **15 Years**

(21) Appl. No.: **29/943,971**

(22) Filed: **May 24, 2024**

(30) **Foreign Application Priority Data**

May 9, 2024 (CN) 202430270408.5

(51) **LOC (14) Cl.** **14-01**

(52) **U.S. Cl.**

USPC **D14/205**

(58) **Field of Classification Search**

USPC D14/205, 206, 207, 217, 221, 223, 225;

(57) **CLAIM**

The ornamental design for a bluetooth headset, as shown and described.

DESCRIPTION

FIG. 1 is a perspective view of a bluetooth headset showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is a bottom plan view thereof.

The broken lines depict portions of the bluetooth headset and form no part of the claimed design.

1 Claim, 8 Drawing Sheets
